Des. 210,644
Patented Mar. 26, 1968

210,644

COMBINED HAIR SPRAY APPLICATOR AND CONTAINER THEREFOR

George B. Douglas, 550 40th St., and Roland C. Eberhardt, 753 W. 8th St., both of San Pedro, Calif. 90731

Filed Feb. 11, 1966, Ser. No. 1,011

Term of patent 7 years

(Cl. D86—10)

FIG.6

FIG. 1 is a top perspective view of a combined hair spray applicator and container therefor showing our new design with the top in an open position and the wand and flexible hose in a stored position.

FIG. 2 is a side elevation thereof with the top in a closed position.

FIG. 3 is a front elevational view thereof.

FIG. 4 is a back view.

FIG. 5 is a top plan view.

FIG. 6 is a bottom plan view.

We claim:

The ornamental design for a combined hair spray applicator and container therefor, substantially as shown and described.
